UNITED STATES PATENT OFFICE.

IVOR REES TITUS AND JOHN WALTON ENSIGN, OF HUNTINGTON, WEST VIRGINIA, ASSIGNORS TO THE ENSIGN MANUFACTURING COMPANY, OF SAME PLACE.

SELF-OILING WHEEL.

SPECIFICATION forming part of Letters Patent No. 602,379, dated April 12, 1898.

Application filed December 8, 1897. Serial No. 660,695. (No model.)

To all whom it may concern:

Be it known that we, IVOR REES TITUS and JOHN WALTON ENSIGN, of Huntington, in the county of Cabell and State of West Virginia, 5 have invented a new and useful Improvement in Self-Oiling Wheels, of which the following is a specification.

The invention is an improvement in the class of wheels commonly known as "self-oiling" wheels, and has for an object to provide a wheel-hub adapted to hold a quantity of oil in such manner as to supply it to the bearing in sufficient quantity to properly lubricate the journal in the most economical manner.

15 It has for further objects to provide means by which to exclude dust from the journal and to provide at a convenient point means by which to supply the oil without the removal of plugs and other devices commonly 20 used for that purpose.

The invention has for further objects other improvements; and it consists in certain novel constructions and combinations of parts, as will be hereinafter described, and pointed out 25 in the claims.

In the drawings, Figure 1 is a longitudinal section of the wheel in place on a spindle. Fig. 2 is a cross-section on about line 2 2 of Fig. 1. Fig. 3 is a cross-section on about line 3 3 of Fig. 1. Fig. 4 is a cross-section on about 30 line 4 4 of Fig. 1, and Fig. 5 is a detail perspective view of one of the check-blocks.

The wheel A has its hub formed with a journal-tube B and with a shell C, an annular intermediate oil-space D being formed between them. At the inner end of the hub the shell C and tube B are connected by lugs E, spaced apart, forming ports or openings F, leading from the bearing to the oil-space near the inner end of the spindle G. The tube B is provided in advance of the ports F with an oil-arresting ledge or shoulder F², as best shown in Fig. 1. The tube and shell are connected near the inner end of the hub by arms C', the inner tube being extended beyond the arms C', so the oil will not fall back into the openings F in large quantities and run to waste at the back end of the journal. The shell is extended inwardly beyond the journal-tube, 45 with its inner end in alignment with said tube,

and is contracted between said end and the arms C', forming a contracted annular passage which leads to the openings or ports F, such passage being further contracted by the annular rib F², which operates as a guard and 55 keeps back the bulk of the oil, and yet allows sufficient to pass to lubricate the axle-collar.

Openings b are provided in the tube B, leading directly to the journal, for the direct passage of the oil to the spindle. 60

At the front end of the hub openings H are provided, leading outward into the space within the tubular extension or nipple I of the shell. The cap J is fitted to this extension I, is shouldered at K, and fitted into a rabbet 65 L, a suitable packing being supplied at such point, and the cap is held by the set-screws M or in other suitable manner. This cap J closes the outer end of the hub, has an opening J' to permit the oil to be supplied at will, 70 and operates at its inner end to hold the check-blocks N in place. These blocks have wings N', fitting in the groove G' of the spindle G, and wings G², which overlap the end of the spindle, the cap fitting at its inner end over 75 the check-blocks and holding the same securely in place, thus fastening the wheel in position on the spindle. These blocks N about at their ends and are provided in their outer sides at such ends with recesses, the recesses 80 in the meeting ends of the adjacent blocks lying opposite each other and communicating, so they unite in forming ports for the oil in directing the same into the oil-space.

In operation the journal will be lubricated 85 thoroughly its entire length with less oil than is ordinarily required, the wheel will be securely held and a better surface than the ordinary cotters will be furnished to receive the wear on the end of the hub, the check-blocks 90 will be positively secured by means of the cap, the wheel can be quickly removed and replaced in the case of repairs or when otherwise desired, and the whole is accomplished in a simple and effective manner. 95

Having thus described our invention, what we claim as new, and desire to secure by Letters Patent, is—

1. The combination of the spindle, the wheel, the check-blocks engaging the spindle 100

and abutting at their ends and having in their outer sides at such ends recesses, the recesses in the meeting ends of the adjacent blocks uniting in forming ports for the oil substantially as shown and described.

2. The improvement herein described comprising the spindle, the series of blocks engaging the spindle, abutting at their ends and having at their ends recesses forming ports for the oil, and means for securing the blocks in engagement with the spindle substantially as set forth.

3. A wheel having its hub formed with a shell and a journal-tube providing an intermediate oil-receptacle, the shell being extended inwardly beyond the journal-tube, spaced lugs connecting such inner extension of the shell with the inner end of the journal-tube and outwardly-extending arms in the oil-receptacle in advance of the said spaced lugs substantially as set forth.

4. The combination of the spindle having a groove the wheel, the check-blocks having

each a wing fitting in the groove of the spindle and a wing which overlaps the end of the spindle and the cap overlapping such blocks at its inner end and secured to the wheel whereby to hold the blocks in place substantially as set forth.

5. A wheel having a journal-tube and a shell the latter being extended at its inner end beyond the inner end of the journal-tube and contracted in advance of said end forming a contracted passage, the spaced lugs connecting the ends of the shell and journal-tube at the inner end of said contracted passage, and the rib in advance of said lugs and operating as a guard whereby to limit the passage of oil to the openings or ports between the spaced lugs substantially as set forth. 40
